UNITED STATES PATENT OFFICE

132,802

DESIGN FOR A STRIP SERVER

Egmont Arens, Southport, Conn., assignor to
Nashua Gummed and Coated Paper Company,
Nashua, N. H., a corporation of Massachusetts

Application January 20, 1942, Serial No. 105,326

Term of patent 14 years

To all whom it may concern:

Be it known that I, Egmont Arens, a citizen of the United States, residing at Southport, county of Fairfield and State of Connecticut, have invented a new, original, and ornamental Design for a Strip Server, of which the following is a specification, reference being had to the accompanying drawing, forming a part thereof.

In the drawing:

Fig. 1 is a perspective view of a strip server, showing my new design; and

Figs. 2 and 3 are front and rear elevational views respectively, of the strip server shown in Fig. 1.

I claim:

The ornamental design for a strip server, substantially as shown.

EGMONT ARENS.
